UNITED STATES PATENT OFFICE.

ROYER LUCKENBACH, OF PHILADELPHIA, PENNSYLVANIA, ASSIGNOR TO LUCKENBACH PROCESSES CO. (INC.), OF SAN FRANCISCO, CALIFORNIA, A CORPORATION OF NEVADA.

APPARATUS FOR CONCENTRATING ORE.

1,397,815.

Specification of Letters Patent. Patented Nov. 22, 1921.

Application filed December 10, 1917. Serial No. 206,410.

To all whom it may concern:

Be it known that I, ROYER LUCKENBACH, a citizen of the United States, and a resident of Philadelphia, county of Philadelphia, 5 and State of Pennsylvania, have invented a certain new and useful Apparatus for Concentrating Ore, of which the following is a specification.

My invention relates to an apparatus for 10 concentrating ore by means of a combined flotation and amalgamation process in which the finer mineral particles in the form of oxids, carbonates as well as sulfids of the minerals acted on will be recovered by 15 means of a flotation process, and the free metal in relatively large particles will be recovered by amalgamation with mercury.

The object of my invention is the production 20 of an apparatus wherein the operation will be continuous, at the expenditure of a minimum amount of power, and wherein the maximum of mineral values will be recovered.

A further object is to provide a device 25 wherein air will be automatically introduced into the pulp to form the froth for flotation of the mineral values.

A further object is to provide means for 30 automatically agitating the pulp so as to bring the mineral particles into contact with the mineral-selective materials.

Another object is to provide means for replenishing the supply of water, and frothing and mineral-selective compound of the pulp.

35 These and further objects will more fully appear in the following specification and accompanying drawings considered together or separately.

I have illustrated one embodiment of my 40 invention in the accompanying drawings in which like parts in all of the figures are designated by similar reference characters and in which—

Figure 1 is a plan view of the apparatus 45 with the replenishing means removed.

Fig. 2 is a side elevation, partly in section of the same, the section being taken on the line 2—2 of Fig. 1.

Fig. 3 is a transverse sectional view of 50 a modification, the section being taken on a line represented by 3—3 in Fig. 1.

Fig. 4 is a side elevation of a modification and

55 Fig. 5 is a detail sectional view of the conical deflector.

In carrying out my invention I preferably provide a plurality of receptacles or tanks, as 1, 2 and 3 communicating with each other in series. The receptacles or tanks are arranged on successively lower levels in order 60 that a liquid or semi-liquid, such as ore pulp may pass from one to the other by means of gravity. The tanks are identical in every respect and a detail description of one will suffice for all.

65 The tank has a hopper bottom 4 provided with a valve 1, whereby the contents of the receptacle or any portion thereof may be drawn off.

The top of the tank is open and is surrounded with a launder 5, provided with a lip 6 by means of which its contents may be directed to any desired point.

Extending downwardly into the tank is a 70 plurality of vertical feed tubes 7 which are open at top and bottom. The tops of the tubes 7 extend some distance above the top of the tank and the lower extremities of the tubes extend into the tank to a point nearer the bottom than the top. Directly below 75 each tube 7 and at a short distance above the bottom of the tank is a conical deflector 8 with its apex toward the mouth of the tube. The tube 7 carries a circular deflector 9 situated a short distance below the top of the 80 tank and the tank is provided with a partition 10 situated a short distance below the deflector 9. The partition has a circular 85 opening 11 concentric with each feed tube 7 and each opening is provided with a depending cylindrical skirt 12.

Communicating with each tube 7 is a pulp 90 supply pipe 13 from a source of supply (not shown).

A water supply pipe 14 extends longitudinally of the apparatus in proximity to the upper end of each series of feed tubes 7, and is provided with a branch 15 communicating with each tube of its series. Each of the branches 15 is provided with a valve 16 in 100 order that the supply of water may be adjusted.

Extending into the upper open end of each feed tube 7 is a pipe 17. The lower end of the pipe 17 is situated some distance below the inlet of the supply pipe 13. The upper end of each pipe 17 is provided with a flared portion or funnel 18 and extending into each funnel is a valved branch 19 of a line pipe 20. There may be a separate 110

line pipe 20 for each series of feed tubes or a line pipe common to all of them may be employed. The water pipe 14 may be arranged in the same manner as is the line pipe 20. The line pipe is preferably connected to a source of frothing and mineral-selective compound supply (not shown) and to a source of mercury supply (not shown) whereby either compound or mercury may be supplied to the tank.

A conduit 21 communicates with the side of the tank immediately below the partition 10, and said conduit forms the pulp supply pipe for the next tank in the series.

15 Within the bottom of each tank 1, 2 and 3 is an electrical contact point 22, all of which are connected to the negative lead 23 of an electric circuit to form cathodes. The positive lead 24 of the circuit is connected 20 to one of the feed tubes 7 and forms the anode. While I have shown but one of the tubes connected in the circuit it will be obvious that one tube of each tank may be so connected, or all of the tubes of the apparatus may be directly connected in the circuit. The leads 22 and 23 are connected up to a suitable source of electrical supply (not shown) and the current supply is of low voltage as compared with the amperage.

30 The preferred current is one volt and twenty amperes.

In the modification shown in Fig. 3 the deflector or baffle plate 9^a instead of being a circular plate secured to each feed tube 7 35 may be a plate common to each tube, and the opening 11^a instead of being circular and individual to each tube may be long enough to provide for the passage of all of the feed tubes of the tank.

40 The operation of my improved apparatus is as follows:—

The bottom of each tank is filled with mercury to a level of about the lower portion of the conical deflector 8. The mercury is 45 preferably introduced through the line pipe 20, and tubes 17, but may be inserted through the feed tube 7 or directly into the tank as desired. When the desired level of the mercury is reached the supply is cut off. The 50 electric current being on, the mercury in each tank now becomes the cathode of the circuit.

A mixture of finely divided ore and water forming a pulp is now admitted to the supply pipe 13 and a frothing and mineral-selective compound is supplied to the line pipe. Any selective and frothing solution containing an electrolyte may be used but I prefer to employ a compound comprising oleic acid, 55 rosin, caustic soda, lime, and shellac. Such a compound is described and claimed in my co-pending application for patent filed August 16, 1917, and numbered serially 186,642.

The valves in the branches 19 are opened 60 to permit the escape of the compound in

proper proportion to the pulp supplied by the feed pipe. The pulp passing down the feed tube 7 will draw air into the tube and this air supply will be augmented by air trapped in the tube 17 by the compound 70 falling into it drop-by-drop.

As the aerated pulp descends the feed tube and issues from the lower open end thereof violent agitation will occur. This agitation will, because of the presence of the 75 air, cause the formation of bubbles in the mass. These bubbles will become coated with a strong film of the mineral-selective compound to which free metal, sulfids, oxids or carbonates will adhere.

When the stream of aerated pulp escapes from the feed tube it impinges on the conical deflector 8. This further agitates the mixture and deflects the heavier portions of the mixture toward the walls of the tank. 85 When the heavier portion of the pulp rises by the pressure in the feed tube it will encounter the partition 10 and will escape through the conduit 21 to the next tank 2. The lighter portion of the pulp, *i.e.* the bubbles, will likewise rise because of the pressure and by gravity but by reason of the fact that the heavier portions, the water and rocky constituent of the ore, have been thrown outward because of their greater specific gravity, the bubbles will rise in a more or less well defined column around each feed tube and escape through the opening in the partition or diaphragm 10 and form a thick, heavy and lasting mineral covered froth. 90 The skirt depending from the opening will prevent the bubbles rising within the zone defined by the skirt from escaping from the tank by means of the conduit 21. The froth will accumulate in that portion of the tank 105 above the partition 10 and will overflow the walls of the tank and be caught in the launder 5 from which it may be removed and the mineral values recovered.

The baffle plate 9 will retard the upward 110 flow of the froth, and will deflect the same outward and cause it to overflow the walls of the tank into the launder.

If the appearance of the froth in the tank 115 1 indicates that the frothing is not proceeding satisfactorily the operator will know that the pulp is too thick or that the supply of "dope" or frothing and selective compound is not properly proportioned to the pulp. If the former be the case the valve 16 will be 120 opened and an additional supply of water will be added to the pulp. If the "dope" supply be objectionable the valve in the branch 19 of the tank will be manipulated and the proper supply admitted to the tank. 125

Any free metallic particles too heavy to be floated by the froth or by the pressure of the stream in the feed tube will fall into the mercury and become amalgamated therewith. The pulp being slightly saline or 130

acid, as the case may be, will act as an electrolyte and the electric current will cause activity of the mercury by reason of the excess of hydrogen created by the current.

5 The pulp entering the conduit 21 will carry some mineral values with it. These particles of mineral may not have come in contact with bubble films in the tank, or they may be particles which could not adhere to 10 the bubbles in that tank by reason of the fact that the bubbles may have taken up all of the mineral they were capable of carrying.

The pulp will be acted on in the tank 2 in the same manner as in the tank 1, and free 15 metal passing out of the latter tank will be taken up by the mercury in tank 2. The water and "dope" removed from the pulp in the tank 1 by the formation of the bubbles will be replenished by supplies from the 20 pipes 14 and 20.

The same operation will take place in any and all succeeding tanks and as a result when the pulp has passed through the system all of the mineral values in all forms 25 will have been recovered.

When it is desired to remove the amalgam from the tanks, the valves at the bottoms of the tanks will be opened, and the amalgam drawn off.

30 If desired, instead of supplying additional water to the pulp as it progresses through the series, untreated pulp may be supplied to the conduits 21 through pipes 13^a between tanks by which means the capacity of the 35 apparatus will be greatly increased.

In Figs. 4 and 5 I have shown a modification of the apparatus wherein the capacity will be very greatly increased. In the form of the device shown in Fig. 4 the tanks 1^a, 40 2^a and 3^a are of the progressively increasing dimensions and capacity. The last tank 4^a of the series may be of the same size and capacity as the one next before it.

Each of the tanks is provided with a 45 conical deflector 8^x, a partition 10 and a baffle 9 as before. The feed tube 7 of each tank is closed at the top. The water pipe 15 and valve 16 are connected as in the form of the device shown in Figs. 1 and 2. A valved 50 supply pipe 19 enters the feed tube and extends to some distance below the top of the tube.

The conical deflector 8^x is a hollow body with its shell foraminous. The openings 8^a 55 in the cone are of flaring shape in order that they may not become choked. Communicating with the interior of the cone 8^x is a pipe 8^b by means of which air under pressure is admitted to the interior of the cone 60 and thence to the pulp in the tank.

The conduit 21 from the tank 1^a is provided with a branch 13^a having a valve 13^b therein. The end 21^a of the conduit 21 which is in communication with the feed 65 tube 7 of the tank 2^a is of increased diameter

to provide for additional pulp from the branch 13^a. The tube 7 of tank 2^a is also of a size sufficient to carry the partly worked pulp from the tank 1^a plus additional untreated pulp supplied by the pipe 13^a. Additional water is supplied by the pipe 15 and "dope" by the pipe 19^a. 70

The conduit 21^b from the tank 2^a communicates with a branch 13^d having a valve 13^e. The end 21^c of the conduit, the feed 75 tube 7 and the tank 3^a are of a size sufficient to take the output of unconcentrated pulp from the tank 21^a plus untreated pulp to the capacity of the branch 13^d.

The system may be carried out indefinitely 80 with elements of gradually increasing capacity. I prefer, however, to construct the last unit 4^a of the system of the same capacity as the unit next preceding it. This unit will have means for introducing water and "dope" 85 into the pulp but no untreated pulp will be added and consequently the pulp in this tank will have had its mineral content partially extracted and the supply of "dope" will be so proportioned to the pulp that the last of 90 the mineral value will be removed from the pulp.

It will be understood that the lower part 95 of each tank is filled with mercury as before described and that a low voltage current is passed through the mercury and pulp in each tank.

The operation of the form of apparatus shown in Fig. 4 is the same as that described above, except that the air instead of being 100 drawn into the tanks through the feed tubes and "dope" pipes is forced in through the conical deflectors. The air, therefore, will not only form the bubbles in the mass but will assist in the agitation and circulation 105 of the pulp and froth.

The supply of materials to the tanks, except the last unit of the series, is preferably so proportioned that the concentrates from each tank, except the last, will equal that of 110 each other tank, it being understood that a very large percentage of mineral is recovered in the initial treatment of the pulp.

I desire to have it understood that I do not desire to limit my invention to the methods of aeration illustrated and described but it is to be understood that air may be introduced into the apparatus in any desired manner.

In accordance with the provisions of the 120 patent statutes I have described the principle of my invention, together with the apparatus which I now consider to represent the best embodiment thereof, but I desire to have it understood that the apparatus shown 125 is merely illustrative, and that the invention may be carried out in other ways.

Having thus described my invention what I now claim as new and desire to secure by Letters Patent, is:

1. An apparatus for concentrating ores, which comprises a tank, a vertically arranged feed tube extending into the tank, means for supplying ore pulp, air and a frothing material to the tube, a conical deflector in the lower portion of the tank and below the tube, whereby the agitation of the pulp issuing from the tube will form bubbles to which mineral values will adhere, the said 5 cone deflecting the heavier ingredients of the pulp outward toward the walls of the tank, there being an outlet from the tank below the top thereof and above the lower extremity of the feed tube, means above the 10 outlet for preventing the heavier ingredients of the pulp from directly rising above the outlet, there being an opening in the last mentioned means whereby the mineral bearing froth may rise above said outlet.
- 15 2. An apparatus for concentrating ores, which comprises a tank, a vertically arranged, centrally located feed tube extending into the tank, means for supplying ore pulp, a frothing material and air to the tube, a 20 conical deflector below and in vertical alinement with the tube whereby the heavier ingredients of the pulp will be directed outward toward the walls of the tank and then upward, there being an outlet from the tank 25 below the top thereof and above the lower extremity of the feed tube for discharging the heavier ingredients of the pulp, and a horizontal partition across the tank above the outlet and below the top of the tank, for 30 preventing the direct upward passage of the material near the walls of the tank, there being an opening in the partition through 35 which the feed tube extends, there being a space between the feed tube and the edge 40 of the opening.
3. An apparatus for concentrating ores, which comprises a tank, a vertically arranged, centrally located pulp feed tube extending into the tank and terminating 45 short of the bottom thereof, a conical deflector below and in axial alinement with the open end of the tube, means for supplying air to the pulp whereby the agitation set up by the flow from the tube will form 50 bubbles to which mineral values will adhere and the gangue particles will be forced outward toward the walls of the tank, there being an outlet from the tank below the top 55 thereof and above the lower extremity of the feed tube, there being a second outlet above the first mentioned outlet, a partition for preventing the passage of the gangue upward above the first mentioned outlet, there being an opening in the partition, and a de- 60 pending skirt or flange circumscribing the opening, said skirt being above the lower end of the feed tube and extending below the level of, and masking the first mentioned outlet.
- 65 4. An apparatus for concentrating ores, comprising a tank, a vertically arranged tube extending into the tank, means for supplying ore pulp to the tube, means for supplying a frothing and mineral-selective material to the tube, a conical deflector within 70 the tank and situated with its apex below the center of the tube, whereby the pulp issuing from the tube will be separated into froth and tailings, a conduit communicating with the tank at a point above the bottom 75 thereof, means for directing the tailings to the conduit, said conduit communicating with the feed tube of a second tank on a lower level than the first mentioned tank, means for supplying untreated pulp to the 80 conduit between the tanks, a conical deflector in the second tank below the outlet of the feed tube, and a conduit communicating with the second tank above the bottom 85 thereof.
5. An apparatus for concentrating ores, comprising a tank, a vertically arranged tube extending into the tank, the upper end of said tube being open to admit air to the tank, means for supplying ore pulp to the 90 tube, means for supplying a frothing and mineral-selective material to the tube, a conical deflector within the tank and situated with its apex below the center of the tube, whereby the pulp, air, and frothing and selective material issuing from the tube will 95 cause a separation of the pulp into froth and tailings, a conduit communicating with the tank at a point above the bottom thereof, means for directing the tailings to the conduit, said conduit communicating with the feed tube of a second tank on a lower level than the first mentioned tank, means for supplying untreated pulp to the conduit between the tanks, means for supplying water to 100 the feed tube of the second tank, means for supplying fresh frothing and mineral selective material to the feed pipe of the second tank, a conical deflector in the second tank below the outlet of the feed tube, and a conduit communicating with the second tank above the bottom thereof. 105
6. An apparatus for concentrating ores, comprising a series of tanks arranged on progressively lower levels, said tanks being 110 of progressively increasing capacity, means for admitting ore pulp to the tank of highest level, means for introducing a frothing and mineral-selective material into the pulp, means for aerating the pulp, means for agitating the pulp to form bubbles, means for 115 passing tailings from one tank to the next lower tank of the series, and means for replenishing the tailings supply between tanks with pulp. 120
7. An apparatus for concentrating ores, comprising a series of tanks arranged on progressively lower levels, said tanks being 125 of progressively increasing capacity, means for admitting ore pulp to the tank of highest 130

- level, means for introducing a frothing and mineral-selective material into the pulp, means for aerating the pulp, means for agitating the pulp to form bubbles, means for 5 passing tailings from one tank to the next lower tank of the series, and means for replenishing the tailings supply between tanks with pulp in progressively increasing amounts.
- 10 8. An apparatus for concentrating ores, comprising a series of tanks arranged on progressively lower levels, said tanks being of progressively increasing capacity, means for admitting ore pulp to the tank of highest 15 level, means for introducing a frothing and mineral-selective material into the pulp, means for aerating the pulp, means for agitating the pulp to form bubbles, means for passing tailings from one tank to the next lower tank of the series, means for adding 20 water to the tailings between tanks, means for adding frothing and mineral-selective material to the tailings between tanks, and means for replenishing the pulp supply between tanks.
